United States Patent Office

Des. 209,463
Patented Dec. 5, 1967

209,463

CEILING-MOUNTED LIGHT FIXTURE

Andrew L. Chako, Lancaster, Calif., assignor to Eagle Manufacturing Co., Industry, Calif., a corporation of California

Filed Oct. 21, 1966, Ser. No. 4,378

Term of patent 14 years

(Cl. D48—7)

Fig. 1

FIGURE 1 is a perspective view, looking slightly upwardly from the front, showing a ceiling-mounted light fixture embodying my new design; and,

I claim:

The ornamental design for a ceiling-mounted light fixture, substantially as shown and described.
